CLEANSING DEVICE FOR ROTARY ROCK DRILLS.

Paul C. O'Leary, Phillipsburg, N. J., assignor to Ingersoll-Rand Company, New York, N. Y., a corporation of New Jersey.

Application August 16, 1952, Serial No. 304,728

2 Claims. (Cl. 255—49)

This invention relates to rock drilling mechanism, and more particularly to a cleansing device for pressure fluid actuated rock drills of the rotary type.

Heretofore, in the use of devices of the type to which the present invention pertains, it has been the practice to utilize the pressure fluid that drives the motor serving to rotate the drilling implement, only for that function and to use a constant stream of pressure fluid directly from the source of supply for blowing the cuttings from the hole being drilled. This mode of operation, in addition to being wasteful of power medium, is also highly objectionable from the standpoint of the noise which results when the fluid is exhausted directly from the motor into the atmosphere.

It is accordingly an object of the present invention to minimize the power cost for operating the rock drill.

Another object is to obviate the objectionable noises occasioned by the exhaust fluid discharging directly from the rock drill to the atmosphere.

Other objects will be in part obvious and in part pointed out hereinafter.

In the drawings accompanying this specification, and in which similar reference numerals refer to similar parts,

Figure 1 is a side elevation, partly broken away, of a rotary rock drill equipped with a cleansing device constructed in accordance with the practice of the invention.

Figure 2 is an elevation, partly in section, of the driving element of the rock drill.

Figure 3 is a similar view of a detail, and

Figure 4 is a transverse view taken through Figure 2 on the line 4—4 looking in the direction indicated by the arrows.

Referring more particularly to the drawings, 20 designates, in general, a rotary rock drill and 21 a drill rod which is rotated by the rock drill 20. The drill rod carries a cutting bit 22 shown as being of the insert-diamond type and extends into the forward end of the casing 23 where it is supported and guided by a pair of relatively spaced, anti-friction, bearings 24 and 25.

Rotary motion is imparted to the drill rod 21 by a pressure fluid actuated motor 26, the casing 27 of which is seated upon a surface 28 at the rearward end of the casing 23 and to which it may be secured in any suitable manner. The motor 26 is of the multi-piston type. Its cylinders 29 are arranged in V-fashion about a crank shaft 30, and each cylinder 29 contains a piston 31, the rod 32 of which is connected to a common crank pin 33 having crank webs 34 and 35. The crank shaft 30 extends forwardly through the casing 23, in parallelism with the drill rod 21, and carries a pinion 36 that meshes with a gear 37 which is carried by the drill rod 21 and located between the bearings 24 and 25.

The distribution of pressure fluid to the cylinders 29 is controlled by a valve 38 arranged in a valve chest 39 mounted upon the rearward end of the motor casing 27. The valve 38 is rotatable within the chest 39, more particularly, within a bushing 40 in the chest, and has a

2

stem 41 that extends into and is interlockingly engaged with the crank web 34 coaxially with the crank shaft 30.

Within the valve 38 is a passage 42 having a port 43 at its forward end for registry with passages 44, in the bushing 40 and in the casing 27, leading to the outer ends of the cylinders 29. The pressure fluid enters the passage 42 through a port 45, in the valve 38, that is in constant communication with an annular groove 46 in the inner surface of the bushing 40 and into which pressure fluid flows from a supply conduit 47 through a passage 48 in the valve chest and in the bushing 40.

In order to prevent the motor speed from rising to an excessively high rate in the event that the cutting bit 22 enters a void or a pocket of soft material in the rock formation, the motor 26 is provided with a suitable governor 49 for controlling the rate of flow of pressure fluid to the valve 38. The governor 49 is interposed in the supply conduit 47 and its housing 50 is mounted upon the rearward end of the casing 27. The governor comprises a spring opposed valve 51 which is reciprocable in the housing 50 for controlling communication between branches 52 and 53 of the supply conduit 47 attached to the housing 50 at points lying in spaced parallel planes.

The valve 51 is actuated for throttling the flow of pressure fluid from one branch conduit to another by centrifugally actuated weights 54 which are pivotally mounted upon a bracket 55 in the housing 50 and have arms 56 in engagement with the end of a stem 57 on the valve 51 for lifting said valve. The bracket 55 is carried by a shaft 58 that extends through the casing 27 and carries a pinion 59 which meshes with a gear 60 on the crank shaft 30.

In addition to effecting the distribution of pressure fluid to the cylinders 29, the valve 38 also controls the exhaust of fluid from the cylinders. It is, accordingly, provided with a passage 61 that extends endwise of the valve, and has a port 62 opening into its periphery for communication with the passages 44. The opposite end of the passage 61 opens into a chamber 63 located in the valve chest 39 at the rearward end of the valve and a conduit 64 extends from the chamber 63 to the casing 23, to which it is attached by bolts 65, for conveying the fluid exhausted by the motor to a chamber 66 in the casing 23 and which chamber is in constant communication with a passage 67 extending from end to end of the drill rod 21. Owing to this arrangement, all of the fluid exhausted by the motor 26 will pass to the working surface for blowing the cuttings from the drill hole.

When drilling dry rock, the amount of fluid thus directed into the drill hole will suffice to keep the working surface free of cuttings, but when drilling rock that is moist the cuttings tend to adhere to the wall of the drill hole, particularly adjacent the cutting bit, and may accumulate in quantities that will clog the drill hole. To the end that occurrences of this nature may be obviated, the rock drill is provided with means for selectively directing an uninterrupted stream of cleansing fluid, at full line pressure, into the drill hole whenever required. A conduit 68 is accordingly extended from the supply conduit 47 to the conduit 64 to bypass the valve 38 and a valve mechanism, designated 69, controls the flow of pressure fluid thereto from supply.

The valve mechanism 69 comprises a casing 70 which is secured to the rock drill casing 23 by bolts 71 and is interposed between the supply conduit 47 and the conduit 68. The casing 70 is recessed to provide a valve chamber 72 and passages 73 and 74 that communicate with the supply conduit 47 and the conduit 68, respectively, and open into the valve chamber 72 at relatively spaced points along its length. Communication between

the passages 73 and 74 is controlled by a valve 75 having a pair of heads 76 and 77 which are connected by a stem 78 around which pressure fluid flows from the passage 73 to the passage 74 in what may be termed the open position of the valve.

The valve 75 normally occupies a position in which the head 76 covers the passage 73. It is held in that position by a spring 79 interposed between the valve and a plug 80 forming a closure for one end of the valve chamber 72. The opposite end of the valve chamber 72 is also closed by a plug 81, and the end of the valve 75 adjacent thereto constitutes an actuating surface 82 which may be selectively subjected to pressure fluid conveyed to it by a conduit 83 connected to the plug 81 and having a manually operable valve 84 whereby the flow of pressure fluid to the actuating surface 82 and the exhaust of such fluid to the atmosphere may be controlled.

In the operation of the device, the valve 38 is rotated by the crank shaft 30 to bring the port 43 successively into registry with the passages 44 for charging the cylinders 29 and the port 62 is brought, in like manner, into communication with the passages 44 for effecting the exhaust of fluid from the cylinders into the chamber 63, whence it passes through the conduit 64, the chamber 66, and through the passage 67 in the drill rod into the drill hole for expelling the cuttings.

Whenever the exhaust fluid from the motor is found to be inadequate to keep the drill hole free of cuttings pressure fluid is valved, by manipulation of the valve 84, to the actuating surface 82 of the valve 75. The valve 75 will then be shifted to uncover the passage 73 and pressure fluid will flow, in an uninterrupted stream, from the passage 73 into the passage 74 through the conduits 68—64 and associated passages into the drill hole.

The valve 84 may be manipulated to vary the pressure value of the fluid acting against the actuating surface 82 for shifting the valve 75 to either a partially or a full open position, depending upon whether it be desired to supply a heavy or a moderate flow of pressure fluid to the hole being drilled. By suitably restricting the pressure fluid through the valve 75 into the conduit 64 the back-pressure adjacent the valve 38 may be held to a sufficiently low value to preclude stalling of the motor and the motor may then continue to rotate the drill rod to assist in breaking up any compacted mass of cuttings that may have accumulated in the drill hole.

From the foregoing description it will be readily apparent to those familiar with the art that by utilizing the exhaust fluid of the motor instead of a constant jet of pressure fluid from supply, as a medium for cleansing the drill hole, the power cost of operating the drill will be greatly minimized. Moreover, the oil entrained in the pressure fluid and which is usually introduced thereto for lubricating the parts to which the pressure fluid has access will also be carried into the drill hole instead of being disseminated in the atmosphere adjacent the drilling site, and the objectionable exhaust noises will be entirely eliminated.

I claim:

1. In a rock drilling mechanism adapted for rotary drilling only and operable by compressed gas, the com-

bination of a rotary drill rod having a passage for conveying such fluid for cleansing therethrough, a rotary type drill bit on the rod, a compressed gas actuated rotation motor connected to drive the drill rod, a compressed gas supply line for the motor, a rotary valve for the motor for controlling the flow of compressed gas to and the exhaust of such gas from the motor, conduit means for conveying such exhaust gas from the rotary valve to the passage, a by-pass line for compressed gas leading from the gas supply line to the conduit means and by-passing the rotary valve, a pressure fluid actuated valve mechanism in the by-pass line to control the flow of such gas therein, said valve mechanism including a casing having inlet and outlet passages communicating with the gas supply line and the by-pass line, respectively, a reciprocable valve member having a cylindrical head sealingly slidable in said casing and interposed between said inlet and outlet passages for controlling the flow of compressed gas therebetween and having a second head at the opposite end thereof having an end face adapted to be exposed to pressure fluid to actuate the valve to its open position, a spring constantly urging the valve member to the shut-off position, a pressure fluid supply conduit to the casing adjacent said end face of the valve; and a manually operable valve in said line adapted to control the flow of such fluid to said end face of the valve.

2. In a rock drilling mechanism for rotary drilling only and operable by compressed gas, the combination of a rotary drill rod having a passage for conveying such fluid for cleansing therethrough, a rotary type drill bit on the rod, a compressed gas actuated rotation motor connected to drive the drill rod, a compressed gas supply line for the motor, a rotary valve for the motor for controlling the flow of compressed gas to and the exhaust of such gas from the motor, conduit means for conveying such exhaust gas from the rotary valve to the passage, a by-pass line for compressed gas leading from the gas supply line to the conduit means and bypassing the rotary valve, a pressure fluid actuated valve mechanism in the by-pass line to control the flow of gas therein consisting of a reciprocating spool type valve member having a pair of heads, a casing having ports associated by the by-pass line and controlled by one of the heads, a supply line to the casing adjacent an end face of the other said head for motive fluid to actuate the valve and, a manually operable valve in the last said supply line to control the flow of fluid therein.
